UNITED STATES PATENT OFFICE.

ROSE M. SHEEHAN, OF SACRAMENTO, CALIFORNIA.

TABLE.

No. 899,267.

Specification of Letters Patent. Patented Sept. 22, 1908.

Application filed May 4, 1908. Serial No. 430,858.

To all whom it may concern:

Be it known that I, ROSE M. SHEEHAN, a citizen of the United States, residing at Sacramento, in the county of Sacramento and State of California, have invented a new and useful Table, of which the following is a specification in such full and clear terms as will enable those skilled in the art to construct and use the same.

10 This invention relates to a table used for the purpose of kindergarten work and teaching, the object being to produce a table that will enable the teacher to sit in the midst of the group of children, or to insert a center 15 piece and use the table for work that does not require the close attention of the teacher to each individual.

Another object of the invention is to make a table that will be easily packed for shipment, the top being cut in several places whereby small packages are made when the table is taken down.

Another object of the invention is to make a gate that will enable the teacher to enter 25 the center of the table without difficulty.

In the drawings in which the same numeral of reference is applied to the same part throughout, Figure 1 is a perspective view of the table with the center removed, Fig. 2 is 30 a perspective view of the table with the center in place, Fig. 3 is a sectional view of the outer ring of the table, Fig. 4 is a sectional view of a portion of the table showing the means used for securing the legs thereto, Fig. 5 is a sectional view of a portion of the 35 table showing the means used to secure one section to another, and Fig. 6 is a bottom plan view of the table.

The table is provided with the legs 1, of 40 which there are four, said legs being secured in any suitable manner to the outer table tops 2, 3, 4 and 5 respectively. The table tops when placed together form an annulus, dowels being used to insure the proper placing 45 of each table section, and hooks 6 are provided at each section to secure the sections from moving away from each other. Between the sections 2 and 3 is placed the gate section 7 which is hinged at 8 and 9, the 50 latch 10 being used to hold the gate in the closed position.

Under each of the main outer sections of the table there is a slide 11 held in place by means of guides 12, the object of the said

slides being to hold a central section 13 in 55 place when the entire surface of the table is to be used for work. This center section is divided in the middle and is hinged at 14 and 15 in order that it may form as small a parcel as the other parts of the table. 60

When it is desired to use the table to instruct a group of children the teacher lets down the gate, takes out the center and then closes the gate, sitting in the center of the table in which position she is able to easily 65 reach a very large number of children, and when the entire surface of the table is desired the slides may be pulled out and the part 13 is put back, the gate closed and the 70 table is complete for any use that may be desired. It will be understood that such a table may be used for other purposes as well as for kindergarten work.

What I claim as new and desire to secure by Letters Patent of the United States is as 75 follows, modifications within the scope of the claims being reserved.

1. In a table, the combination of an annular sectional top, means to secure each section to its adjacent section, and an entrance 80 section hinged to the annular top.

2. In a table, the combination of an annular sectional top supported by legs, means to secure each section to its adjacent section, a hinged entrance section, and a removable 85 central section.

3. In a table, the combination of an annular sectional top supported by legs, means to secure each section to its adjacent section, a hinged entrance section, a central section 90 adapted to fit the annulus, and slides carried by the annulus for supporting the central section.

4. In a table, the combination of an annular sectional top supported by legs, means to 95 secure each section to its adjacent section, a hinged entrance section, a hinged two part central section adapted to fit the annulus, and slides carried by the annulus and adapted to support the central section. 100

In testimony whereof I have set my hand this 14th day of April A. D. 1908, in the presence of the two subscribed witnesses.

ROSE M. SHEEHAN.
